MANUFACTURE OF SHOES

Maxwell E. Duckoff, Manchester, N. H., assignor to United Shoe Machinery Corporation, Borough of Flemington, N. J., a corporation of New Jersey

Application July 3, 1937, Serial No. 151,884

3 Claims. (Cl. 12—142)

This invention relates to improvements in methods of shoemaking and is herein illustrated with reference to the manufacture of shoes the inner and outer soles of which have complementary interfitting portions in their foreparts.

The invention provides an improved method of making shoes which, as herein illustrated, comprises positioning upon the central portion only of the forepart of an insole on a last a stiff lasting piece smaller than the forepart of the insole but corresponding to the latter in marginal contour, the lasting piece having an upstanding rib extending entirely around its periphery, driving tacks through the lasting piece and the insole into the bottom of the last and thus removably securing the lasting piece and the insole to the last and reinforcing the forepart of the insole, placing an upper on the last, applying cement between the margin of the insole and the margin of the upper, working the upper at the shank over the insole and securing it to the body of the insole, working the upper over the forepart of the insole into lasted position against the rib of the lasting piece and inserting fastenings through the upper to secure it temporarily to the rib, trimming off those portions of the rib and the upper which are secured together after the cement has become set, and thereafter withdrawing the tacks, removing the remainder of the lasting piece and attaching an outsole. The rib of the lasting piece performs the function of the lasting lip which, in accordance with a well-known practice, is formed upon the marginal portion of an insole as by channeling the insole and turning up the channel flap or by stitching a tape to the insole. Thus, the use of the ribbed lasting piece enables the lasting operation to be accomplished by means of a machine of the type employing a gripper for tensioning successive portions of the upper over the last, each tensioned portion being laid in intimate contact with the margin of the insole and secured in lasted position by a staple driven through the upper and the insole lip thereby insuring tighter and better lasting of the shoe. The rib is formed by molding or otherwise, as an integral part of the lasting piece and the latter is preferably composed of stiff tough fiberboard or the like. The rib which extends entirely around the periphery of the lasting piece serves to stiffen it so that the lasting piece will more effectively reinforce the insole forepart and will prevent it from buckling under the influence of the inward wiping movements of the lasting instrumentalities. Furthermore, the construction of the rib is

such that it cannot be deflected from its upstanding position by the strains of the lasting operation or by strains due to the reaction of the lasted upper. Consequently, the rib will effectively withstand such strains and after the upper has been temporarily secured to the rib, the tension of the upper will be positively maintained during the setting of cement employed for permanently securing the upper to the insole and thus the formation of any undesirable fullness or wrinkles in the lasted upper will be avoided.

The use of the improved lasting piece is particularly advantageous in the manufacture of shoes having skeletonized insoles because of the difficulties of channeling the rand-like foreparts of such insoles and the expense of stitching a tape thereto for the purpose of providing a lasting lip. As shown, the lasting piece is secured to the last by means of tacks which also extend through the rand-like forepart of the skeleton insole and thus assist in reinforcing the latter against being stretched as a result of the reaction of the lasted upper. Preferably, however, a reinforcing piece or patch of strong fabric or the like is applied to the forepart of the skeleton insole so as to cover the opening therein and is firmly cemented to the rand portion of the insole, thereby even more effectively reinforcing the insole forepart against stretching or deformation. Preferably, and as shown, this reinforcing piece is applied to the outsole-facing side of the insole and is permitted to remain in the finished shoe where it functions to reinforce the insole throughout the life of the shoe.

The invention will be explained with reference to the accompanying drawings, in which:

Fig. 1 is a perspective view of the forward portion of an insole used in the practice of my improved method showing the side of the insole which is to face the outsole;

Fig. 2 is a perspective view of the forward portion of the outsole showing the upper side thereof;

Fig. 3 is a perspective view of an insole reinforcing patch which is preferably used in the practice of my method;

Fig. 4 is a perspective view of the blank from which the improved lasting piece is made;

Fig. 5 is a sectional view illustrating the method of molding the lasting piece;

Fig. 6 is a perspective view of the lasting piece as it appears after having been molded;

Fig. 7 is a perspective view of the insole together with the lasting piece and other associated parts as they appear after the insole has been secured to the bottom of the last;

Fig. 8 is a cross-sectional view taken substantially along the line VIII—VIII of Fig. 7 and showing also the upper materials as they appear after having been placed upon the last;

5 Fig. 9 is a cross-sectional view illustrating the operation of securing the lasted upper to the rib of the lasting piece;

10 Fig. 10 is a perspective view of the shoe as it appears after the lasting of the upper has been completed;

15 Fig. 11 is a perspective view of the shoe in a later stage of manufacture;

Fig. 12 is a cross-sectional view taken along the line XII—XII of Fig. 11;

20 Fig. 13 is a view similar to Fig. 12 but illustrating the shoe as it appears after the lasting piece has been entirely removed;

25 Fig. 14 is a fragmentary cross-sectional view taken along the line XIV—XIV of Fig. 10;

30 Fig. 15 is a fragmentary cross-sectional view of the shoe as it appears after the outsole has been attached; and

35 Fig. 16 is a view similar to Fig. 15 but showing an alternative form of construction.

40 In the drawings, the invention has been illustrated in its application to the manufacture of shoes the bottoms of which are provided in their foreparts with complementary interfitting portions for the purpose of rendering them more flexible. As shown, the shoe bottom comprises an insole 20 having a central opening 22 in its forepart, and an outsole 24 provided with a central forepart projection 26 that is complementary to the opening in the insole. The insole opening

45 22 is defined by a beveled surface 31 that is formed upon the rand-like forepart 32 of the insole and is complementary to a beveled surface 33 which constitutes the marginal portion of the outsole projection 26. For the purpose of still further increasing the flexibility of the shoe bottom the projection 26 on the outsole is herein shown as having formed therein a series of transversely disposed open cuts or grooves 28 which are V-shaped in cross-section, while the insole

50 20 is provided, upon the side which is to face the outsole, with a series of transverse cuts or slits 30 which extend only part way through the marginal portion of its forepart.

55 In order to insure that the skeleton forepart of the insole will not be stretched or deformed, either by the reaction of the lasted upper during the manufacture of the shoe or as a result of strains to which the insole forepart is to be subjected during the wearing of the shoe, it is preferred to strengthen the insole by cementing to its slit forepart a reinforcing piece or patch

60 34. Advantageously, the reinforcing patch 34 may consist of a thin piece of woven fabric, preferably cut on the bias and shaped so as to adapt it to cover the insole opening 22 and bridge the slits 30. As shown, the reinforcing patch 34, which is to be retained as a permanent reinforcing member, is applied to that side of the insole which is to face the outsole and is secured to

65 the beveled and slit surface of the insole by means of cement. Thus, in the finished shoe, the edge of the reinforcing piece 34 will not be exposed at the foot-engaging side of the insole where, in the absence of a sock lining in the forepart of the shoe, it might tend to irritate the foot.

70 The reinforcing patch 34, in addition to strengthening the shoe bottom, will serve also to cover the open grooves 28 in the outsole projection 26 so as to insure that a smooth surface will be presented to the foot in the central forepart of

the shoe bottom even if no sock lining is used. Furthermore, the cementing of the reinforcing patch to the insole in the manner described will prevent the thin inner edge 36 of the rand-like forepart of the insole from curling upwardly in 5 a manner to cause discomfort to the foot during the wearing of the shoe.

It is also preferred to reinforce the insole by securing to that side which is to face the outsole a shank stiffener 40 and a heel and shank 10 reinforcing piece 42, the latter, as shown, being substantially coextensive with the heel and shank portions of the insole. Advantageously, the shank stiffener 40 may be interposed between the reinforcing piece 42 and the insole and the reinforcing piece may be attached to the insole by means of cement. It may be found desirable to coat the surfaces of the insole and the reinforcing piece which are to engage one another with cement before those parts are assembled 20 and thereafter to assemble the parts by placing the insole on a last or form, locating the shank stiffener upon the insole (the shank stiffener being longitudinally curved to conform to the curvature of the last or form), laying the reinforcing piece upon the insole over the shank stiffener, and finally attaching the parts by pressing them against the last or form by means of a yielding pad thereby at the same time molding the reinforcing piece and the corresponding portion of the insole into conformity with the curvature of the last bottom. It may also be desirable to employ wire staples 44 (Fig. 7) for securing the reinforcing piece 42 to the insole 20, 25 either to supplement the cement attachment or as the sole means for attaching the reinforcing piece.

30 In order to facilitate the lasting of the forepart of the shoe upper and the securing of its lasting allowance by cement to the insole there is assembled with the insole 20, upon a last 46, a lasting piece 48 which is preferably made of thin stiff material such as fiberboard. As herein shown, the lasting piece 48 is of a marginal contour corresponding substantially to that of the forepart 45 only of the insole and it is formed with an endless upstanding rib 50 which extends entirely around the periphery of the piece and effectively reinforces it against bending about axes extending either lengthwise or crosswise thereof. 50 The lasting piece is substantially smaller than the forepart of the insole, however, so that when positioned centrally thereon the marginal rib 50 will be spaced inwardly from the edge of the insole so as to leave exposed a narrow marginal 55 portion 52 (Fig. 7) around the forepart of the insole for receiving the lasting allowance of the upper. The rib 50 of the lasting piece is thus adapted to serve as a lasting lip and shoulder to which an upper may be temporarily secured so that it will be held in place during the setting of lasting cement which is to be used to secure the upper to the marginal portion of the insole.

60 As shown in Fig. 4, the lasting piece is cut large enough to allow for the subsequent upturning of 65 the rib 50 and this operation is preferably accomplished by molding the lasting piece between the cooperating dies, such as the dies 54 and 56 (Fig. 5), the marginal portions of which are shaped to upturn the edge portions of the lasting 70 piece so as to form an endless rib around its periphery which is substantially perpendicular to the flat bottom surface of the lasting piece. If used with a skeleton insole, such as the insole 20, the lasting piece preferably corresponds sub- 75

stantially in both shape and size to that of the space within the outer edge of the beveled surface 31 which defines the forepart opening in the insole. Thus, the lasting piece is adapted to overlap 5 the beveled surface 31 of the insole substantially to the same extent as the reinforcing patch.

The lasting piece 48 is laid over the forepart of the insole 28 on the last in the position shown in Fig. 7 and both the lasting piece and the insole 10 are removably secured to the last by means of tacks 60 which are driven through the lasting piece, the reinforcing patch, the insole, and into the last. As shown, the tacks extend through the beveled portion of the insole and thus serve, in 15 addition to the reinforcing patch, to reinforce the skeleton forepart of the insole against being stretched or deformed by the reaction of the lasted upper while it is on the last.

Shoe upper materials comprising an upper 64 20 and a lining 66 are now assembled with the insole on the last and pulled over in the usual way. Cement, for example water dispersed rubber cement, is applied along the inner surface of the lasting allowance of the upper and the lining, as 25 indicated at 68 and 70, respectively, in Fig. 8, and around the margin 52 of the forepart of the insole, as indicated at 72, and preferably also along the opposite marginal portions of the reinforcing piece 42 (the cement on the reinforcing piece being indicated at 74 in Fig. 14).

The upper may then be lasted at opposite sides of the shank portion of the shoe by means, for example, of a machine of the type disclosed in Letters Patent of the United States No. 1,815,297, 35 granted July 21, 1931, upon application of George Goddu, the machine operating to tension the upper and to drive staples 76 through the lasted upper materials, the reinforcing piece 42 and into the insole 20, the legs of the staples being 40 curved within the material of the reinforcing piece and the insole without penetrating the inner surface of the insole, as illustrated in Fig. 14.

The lasting operation at the forepart of the 45 shoe may next be performed by the use, for example, of a machine of the type disclosed in Letters Patent of the United States No. 1,796,451, granted March 17, 1931, upon application of George Goddu. In the operation of lasting the 50 upper at the forepart of the shoe the upper is seized by a gripper 80, tensioned upwardly, and drawn over the insole, after which a staple nozzle 82 engages the upper and forces it while under tension into the angle between the marginal portion of the insole and the rib 50 of the lasting piece 48, the rib at this time being backed up by a guiding and clinching tool or anvil 84, as 55 shown in Fig. 9. A staple 86 is then driven through the upper materials and through the rib 50, the points of the staples being clinched against the inner surface of the rib by the anvil 84.

Although the forepart lasting operation may 65 be continued around the toe portion of the shoe so as to last the toe, it is usually preferable to employ end embracing wipers in this operation such as are provided by the well-known Bed Lasting Machine. If such wipers are employed 70 for lasting the toe the upper may advantageously be held in overlasted position upon the insole by the application of a binding wire 88 the ends of which may be secured to anchoring tacks, such as the tack 90 shown in Fig. 10. The heel seat portion of the shoe may be lasted in any usual man-

ner and the upper secured in place upon the insole by means of tacks 92.

During the lasting of the forepart the lasting piece 48, stiffened by its marginal rib 50, will effectively reinforce the skeleton insole against any 5 tendency to buckle under the inward wiping action of the staple nozzle 82. Due to the inherent stiffness of the rib and its endless formation which further strengthens it, the rib will not bend outwardly or become deformed by the reaction of the lasted upper with the result that the upper is not permitted to develop any slackness or wrinkles and a smoother and more tightly lasted shoe will be produced. Moreover, the reinforcing patch and the tacks 60 serve to prevent 10 the skeleton insole from being stretched or distorted by any reactive strains which may occur immediately after the lasting has been completed.

After the lasting cement has become set the 15 surplus allowance of the upper, together with the rib 50 of the lasting piece 48, are trimmed off beneath the line of staples, the trimming operation being facilitated by the fact that the presence of the rib on the lasting piece presents the upper materials in an upstanding position where they 20 are readily accessible to the trimming instrumentalities. At the completion of the trimming operation the tacks are pulled and the remainder of the lasting piece 48 is removed.

The lasting piece 48 may be readily removed 25 after the tacks 60 have been withdrawn, inasmuch as the tacks are the only means employed for securing it in place. The removal of the tacks 60 also frees the insole from the last, leaving 30 the last free to be withdrawn from the shoe after the latter has been completed. Preferably, the reinforcing piece 34 is left cemented to the insole and is allowed to remain in the finished shoe where it performs the important function of reinforcing the rand-like forepart of the insole 35 against any tendency of the latter to become stretched or distorted by any strains to which it is subjected during the wearing of the shoe.

As illustrated in Fig. 15, a filler piece 96 of felt or other soft and yielding material may be laid 40 over the reinforcing piece 34 to assist in filling the space within the overlasted margins of the upper materials and to serve as means for cushioning the foot. The use of such filler piece is particularly advantageous in cases where flat-bottomed lasts are employed inasmuch as it 45 serves as a means for supporting the outsole so as to obtain a desired round-bottom effect in the bottom of the shoe. The filler piece may be cut out so as to correspond in edge contour with 50 that of the lasting piece and thus preshaped so as to fit accurately within the space to which it is to be applied.

The shoe is now ready to receive the outsole 55 24 and the latter may be attached permanently 60 by cement in any well-known manner to the overlasted margins of the upper, as indicated in Fig. 15, or it may be attached in any other suitable manner as by means of through-and-through stitching after the last has been withdrawn. The 65 usual full-length sock lining may be applied, or, if desired, a short sock lining may be employed to cover only the heel and shank portions of the shoe bottom inasmuch as the reinforcing piece 34 will serve as a covering for the filler piece 96 70 or for the outsole projection 26 in case no filler piece is used. In either case the open grooves 28 in the outsole projection will be covered so that they cannot cause discomfort to the foot. Furthermore, inasmuch as the reinforcing piece 75

34 is cemented to the beveled inner margin of the rand-like forepart of the skeleton insole, the thin inner edge of the latter will be held in place so that it will have no tendency to curl upwardly during the wearing of the shoe. If desired, the filler piece 96 may be omitted in which case the outsole will be applied with the projection 26 in intimate engagement with the reinforcing piece 34, as shown in Fig. 16.

10 Having described my invention, what I claim as new and desire to secure by Letters Patent of the United States is:

1. That improvement in methods of making shoes which consists in providing an insole having a central forepart opening, an outsole having a central forepart projection complementary to said insole opening, and a lasting piece corresponding in edge contour to that of the forepart and having an upstanding marginal lasting rib extending entirely around its periphery, applying a reinforcing piece to said insole forepart so as to extend across said opening and cementing the margin of said piece to the margin of said insole, placing said insole on a last, positioning said lasting piece upon the insole over said reinforcing piece, temporarily securing said parts to the last, assembling an upper with said parts on the last, applying adhesive between the margin of the insole and the lasting allowance of the upper, forcing the adhesive-treated parts into contact, temporarily fastening the lasting allowance to said rib, permitting the adhesive to set, cutting off the surplus lasting allowance in the forepart only of the shoe together with that portion of said rib to which the lasting allowance is temporarily fastened, removing the remainder of said lasting piece but leaving said reinforcing piece secured to said insole, and attaching the outsole with its forepart projection fitting within the opening in said insole and being covered by said reinforcing piece.

2. In shoemaking methods, that improvement which consists in providing a lasting piece of thin stiff sheet material corresponding in shape to but smaller than that of the forepart of a skeleton insole with which it is to be used and having its marginal portion upturned to form an endless lasting lip, applying a reinforcing piece to the forepart of the skeleton insole so as to cover the opening therein and overlap the rand portion of the insole and permanently securing said piece to said rand portion, positioning said insole upon the bottom of a last with said reinforcing piece outermost, positioning said lasting

piece over said reinforcing piece with said lip spaced inwardly from the edge of the insole to expose a marginal portion around the forepart of the insole, temporarily securing the lasting piece and the reinforced insole to the last, working an upper over the last, securing the upper to the insole in the shank portion of the latter, applying cement between the marginal portion of the forepart of the upper and said marginal portion of the insole, securing the upper to said lasting lip and against said marginal portion of the insole, trimming off the attached portions of said lip and said upper after said cement has set, removing the remainder of said lasting piece without removing said reinforcing piece, and attaching an outsole.

3. That improvement in methods of making shoes which consists in providing an insole having a forepart opening surrounded by a marginal rand portion, an outsole having a central forepart projection complementary to said insole opening, and a lasting piece corresponding in edge contour to that of the insole forepart and having an upstanding marginal lasting rib extending entirely around its periphery, the rand portion of said insole having a plurality of transverse slits in its outsole-facing side, applying to the forepart of said insole a reinforcing piece of the same size as said lasting piece and cementing said reinforcing piece to said rand portion of the insole at the side which is to face the outsole so as to bridge said insole opening and to cover said slits, placing said insole upon a last, positioning said lasting piece upon the insole over said reinforcing piece, driving tacks through the lasting piece and through the reinforcing piece and the insole and into said last temporarily to secure said members together, assembling an upper with said parts on the last, applying adhesive between said rand portion of the insole and the lasting allowance of the upper, forcing the adhesive-treated parts into contact, temporarily fastening the lasting allowance to said rib, permitting the adhesive to set, cutting off the surplus lasting allowance in the forepart only of the shoe together with that portion of said rib to which the lasting allowance is temporarily fastened, withdrawing said tacks and removing the remainder of said lasting piece but leaving said reinforcing piece secured to said insole, and attaching the outsole with its forepart projection fitting within the opening in said insole and being covered by said reinforcing piece.

MAXWELL E. DUCKOFF.
